WALL STRUCTURE

Edward L. Soule, Oakland, Calif.

Application October 23, 1935, Serial No. 46,367

1 Claim. (Cl. 72—115)

This invention relates to wall structures such as exterior building walls, partitions, and the like, and especially to a metal stud for use in building hollow walls, together with means for attaching 5 expanded metal lath, or the like, thereto.

The object of the present invention is generally to improve and simplify the construction of walls and interior partitions in the erection of buildings and like structures; to provide a metal 10 stud in the form of a channel, an I-beam, or the like, which is provided with means for receiving and securing expanded metal lath, wire mesh, or the like; and, further, to provide attachable clips which are provided with means for receiving 15 and securing the lath.

The invention is shown by way of illustration in the accompanying drawing, in which—

Fig. 1 is a vertical cross section of a wall or partition structure;

Fig. 2 is a partial side elevation of Fig. 1;

Fig. 3 is a perspective view of the form of stud employed in the construction shown in Figs. 1 and 2;

Fig. 4 shows a modified form of the stud shown in Fig. 1;

Fig. 5 shows a stud having a clip attached thereto with bendable tongues to receive and secure the metal lath;

Fig. 6 shows a portion of a stud with a clip attached thereto, said clip being provided with tie wires to receive and secure the metal lath;

Fig. 7 is a cross section taken on line VII—VII of Fig. 5;

Fig. 8 is a cross section taken on line VIII—VIII of Fig. 6.

Referring to the drawing in detail, and particularly Figs. 3 and 5, it will be noted that the stud 40 employed is constructed of metal which may be rolled or pressed and that the studs may assume the form of a channel, an I-beam, or otherwise. The webs of the studs are cut out as indicated at 2, 3 and 4, see Fig. 1, to form a truss structure rigid but light in weight and of substantially equal strength both in its chord section 45 and web. The chords or flanges of the studs are cut or punched to form V-shaped openings 5 and tongues 6, which are pressed or bent inwardly to form a stop and securing member for the headed ends of nails 7 placed in the V-shaped 50 openings. In Figs. 1, 2 and 3 the tongues are shown as bent inwardly from the flanges of the studs. In Fig. 4 they are shown as bent outwardly.

As a substitute for cutting or punching the 55 flanges of the studs metal clips, such as shown at

8 and 9 in Figs. 5 and 6, may be employed. These clips are also constructed of metal and they are either punched to receive and retain U-shaped tie wires 11, as shown in Fig. 6, or punched to form a series of outwardly extending tongues 12, 5 shown in Fig. 5. The clips may be made of suitable length and are provided with side flanges 14 to embrace the flanges of the studs and to permit the clips to be secured thereto.

In actual practice the studs are vertically positioned in the wall or partition structure and are welded, or otherwise secured therein. If the type of studs, shown in Figs. 1 to 3, are employed 10 nails 7 are inserted in the V-shaped openings as shown in Fig. 3, the nails being there secured by 15 bending the tongues as shown at 15; that is, the tongues when bent against the heads of the nails prevent inward movement of the nails, while outward movement is prevented as the heads of the 20 nails are secured by the shoulders formed by the narrow V-ends of the openings. After the nails are placed the expanded metal lath is applied and is secured by bending the nails over the lath as 25 shown at 16. Where the tongues are bent outwardly, as shown in Fig. 4, the lath is applied directly thereto and the tongues are bent over, as shown at 17, to secure the lath in place. The same procedure is used when the clips shown in 30 Fig. 5 are employed. That is, the tongues will pass through the lath and the lath will be secured by bending the tongues over the lath. With the clips shown in Fig. 6, the wire ends will 35 pass through the lath hence it will only be necessary to twist the wire ends, as shown at 18, to secure the lath in place.

A wall or partition constructed in the manner 40 here described is hollow and open from end to end and as such provides a dead air space which insulates against heat and cold, and also renders the walls or partitions substantially soundproof. 45 The type of stud employed affords great strength and rigidity, and the open spaces provided, indicated at 2, 3 and 4, permit the placing of wiring, conduits, piping and the like. The tongues punched from the flanges permit quick application and securing of the lath.

The material employed throughout is metal 50 and as such permits welding, thereby insuring further rigidity and strength.

While the invention has been particularly described in connection with the construction of 55 hollow walls, partitions, and the like, it lends itself equally to the construction of hollow floors, etc. Plainly speaking, the channels and I-beams disclosed may be designed and used as joists, 55

studs, rafters, floor beams, girders, or columns, and while other features of the invention are more or less specifically described it should be understood that varying changes may be resorted to within the scope of the appended claim.

5 Similarly, that the materials and finish of the several parts employed may be such as the manufacturer may decide, or varying conditions or uses may demand.

10 Having thus described my invention, what I claim and desire to secure by Letters Patent is:—
The combination with a flange of an I-beam,

of an elongated metal clip extending crosswise of the outer face of the I-beam flange, side flanges formed on the clip and bendable to engage the inner faces of the I-beam flange, and a plurality of U-shaped tie wires extending through perforations formed in the clip, said tie wires adapted to be passed through lath applied to the face of the I-beams and to be twisted exterior of the faces of the lath to secure the lath to the I-beams. 5

10 EDWARD L. SOULE.
